UNITED STATES PATENT OFFICE.

CHARLES W. BABCOCK, OF WATERLOO, IOWA.

AUXILIARY LOCKING MEANS FOR VAULTS.

1,426,946.

Specification of Letters Patent. Patented Aug. 22, 1922.

Application filed January 20, 1922. Serial No. 530,577.

To all whom it may concern:

Be it known that I, CHARLES W. BABCOCK, a citizen of the United States of America, and a resident of Waterloo, Blackhawk County, Iowa, have invented certain new and useful Improvements in Auxiliary Locking Means for Vaults, of which the following is a specification.

My invention relates to improvements in auxiliary locking means for vaults, safes and the like. The object of my improvement is to supply additional locking devices associated with the usual locking-bolts and combination-lock on a vault or safe door, certain parts being placed in close apposition to the lock and to a vulnerable region of the door to either become terminally displaced or broken when the lock is forced or when such vulnerable place is affected by a high degree of heat, to thus release movable locking means from tension, and prevent releasing of the usual locking elements. This renders the door invulnerable to violent intrusions by burglars or others.

This object has been attained by the means which are hereinafter described and claimed and which is illustrated in the accompanying drawings, in which Figs. 1 and 2 are like fragmentary elevations of the inner face of a vault or safe door and of its locking elements, showing my improved auxiliary locking means applied thereto, for automatic actuation when attacked, Fig. 1 being a representation of the auxiliary devices as positioned and tensionally set out of locking engagement, and Fig. 2 showing the released positions of the parts of the device when certain parts are displaced or broken. Fig. 3 is a side elevation of the connected locking elements of the device in untensioned condition, with parts sectioned or broken away and on a larger scale, and Fig. 4 is an under plan view of the same, also with parts sectioned or broken away. Fig. 5 is a cross section of said device taken on the broken line 5—5 in Fig. 3.

Similar numerals of reference denote corresponding parts throughout the several views.

21 represents part of a door of a vault or safe having on its inner face a fixed marginal strip or rib 26 whose outer edge is

flush with the outer edge of the door and 55 near the jamb part 22 of the adjacent stationary wall of the vault. The rib 26 is orificed in different places transversely parallel with the adjacent face of the door to slidingly seat certain locking-bolts such 60 as one or more bolts 24 of the usual locking equipment, and bolts 12 of my auxiliary locking device, and said rib also has positioned medially between the latter orifices a threaded bolt-hole to receive the outer 65 end of a headless bolt 1 which is exteriorly threaded terminally and secured at its outer end to said rib by a nut 5. The bolt 24 is secured to a vertical shifting-bar 23, and the latter has a limited play to and from 70 the rib 26 as required in the locking or unlocking of the door. Inserted in a receiving opening or socket in said door and in a housing on the inner face thereof is the usual combination-lock 25 having a lock-bar connection with said shifting-bar 23.

Referring now to Figs. 3 to 5 inclusive in which is shown the tensionally regulated locking elements of my device, the numeral 3 denotes a cylindrical enlargement cylindrically and concentrically formed integrally on the bolt 1 spaced from its inner end, a nut 2 being mounted on said inner end spaced from said enlargement. A number of like flat rings 4 are mounted 80 loosely upon that part of the bolt 1 which is between the nut 2 and the enlargement 3 and are freely movable relative to each other. As shown in Fig. 5, the hollow of these rings is of greater diameter than said bolt, while the exterior diameter of the rings is the same as the diameter of the enlargement 3. The numeral 7 denotes a cross-bar or plunger-head having a medial cylindrical orifice or bearing seat in which 85 the enlargement 3 is slidably mounted, but this medial orifice is nearer one longitudinal edge of the cross-bar than the other for a purpose to be described. In the same 90 vertical longitudinal plane that traverses the axis of said orifice are parallel cylindrical orifices or seats in opposite ends of the cross-bar 7 in which are mounted the inner ends of the like cylindric locking-bolts 12. In order to releasably secure these 95 ends of said bolts to the cross-bar, both are provided with registering openings 13 to receive short headed pins 14, the latter 100 105

being made of soft metal easily ruptured on occasion to allow withdrawal of the bolts from their seats. The outer ends of the bolts 12 may be provided with vertical transverse holes 15 whose lower parts are diminished in diameter to provide interior shoulders. Short headed pins 16 are inserted in these openings so that when these extremities of the bolts are projected through the orifices in the rib 26, these pins will drop by gravity with their lower ends depending from the bolts to serve as means for preventing unauthorized pushing of the bolts back out of engagement with the structure 22. These pins 16 may be pushed up into the openings 15 before the bolts are withdrawn and while setting the device tensionally so as to not have any projecting parts as these openings are then concealed within the orifices of the rib 26.

The numeral 8 denotes a pair of terminally threaded pins or brackets positioned above and below the bolt 1 in the same vertical plane and having their inner ends secured in threaded sockets in said cross-bar 7. A terminally orificed and medially orificed cross-bar 9 is mounted to slide from the middle portion of the bolt 1 with the outer threaded ends of the pins 8 passed through its terminal orifices and secured by nuts 10. A strong coiled spring 11 is mounted on the middle part of the bolt 1 and engaged between said cross-bar 9 and the said enlargement 3 of the bolt 1. A knurled adjusting nut 6 is mounted on the outer threaded portion of the bolt 1 to adjustably engage said rib 26.

In the lower end of the cross-bar 7 is drilled a vertical hole 19 to receive the upper part of the stem of a hook 17 said stem also traversing an open socket or pit 18 formed in the inner vertical face of the cross-bar 7. Flexible alined wire sections 34 are connected by a turn-buckle 35 for adjusting the tension thereof, the lower end of the lower section 34 being secured at 33 to the inner face of the door medially below the combination lock 25, said section being carried medially across the lock contactingly and obliquely over a housed sheave or pulley 32 which prevents lateral swinging of the section. The other section 34 is carried over a pulley 31 then vertically upward and has a terminal loop passed over said hook 17. Another flexible wire, made up of two sections 28 has its sections likewise adjustably connected by a turn-buckle 36 depending vertically from and having its upper end passed over a pulley 27 with a terminal loop passed about that part of the stem of said hook 17 which is within the pit or socket 18. The lower end of the wire 28 is fixedly secured at 30 to the inner face of said door, and the wire has in its lower section a part 29 made of easily fusible material and which

overlies and contacts with the heat vulnerable part of the door including the locking-bar of the lock and between said lock and the bar 23.

The device may be tensionally set by 70 manually lifting the rings 4 to become coaxial with said bolt 1 and then moving the cross-bar 7 to the left, whereby said rings 4 are received within the medial orifice of said cross-bar while simultaneously, the other cross-bar 9 places the spring 11 under compression. As previously mentioned, the gravity-pins 16 should be lifted manually before the cross-bar 7 is so shifted. The stem of the hook 17 has a close enough fit 80 in the hole 19 so as to require a slight amount of force to withdraw it. As shown in Fig. 1, the looped upper end of the wire 28 should be inserted in the socket or pit 18 before the hook 17 is inserted and after the 85 cross-bar 7 has been moved against the stop-nut 2, whereby the wire 28 is placed under tension and also the coiled spring 11 is held under tension, while the hook 17 is so clasped as to only be withdrawn as above stated by 90 a reasonable amount of force applied to it. The upper looped end of the other wire 34 is then mounted upon the hook 17, in both cases said wires being kept under some strain by the use of the turn-buckles 35 and 95 36 as may be suitable to keep the lower wire parts in juxtaposition to the adjacent lock and door structures. As thus set the device is quiescent and does not interfere with the usual operation of the locking means on said 100 door.

In case the part 25 of said combination lock is forced inwardly from its housing, it forces the lower part of the wire 34 away from the door so that the considerable strain 105 upon the hook 17 pulls the latter out thus also freeing the upper part or loop of the other wire 28. As this releases the coiled spring 11, the reaction of the latter pushes outwardly the cross-bars 9 and 7 together 110 with the locking-bolts 12 to the locking positions shown in Fig. 2. The outer ends of the bolts 12 then project over the jamb 22, and as the headed pins 16 drop by gravity, are prevented from being pushed back. As 115 the cross-bar 7 has a greater width between the bolt 1 and enlargement 3 and its outer vertical edge than on the opposite side, this additional width of the bolt is positioned in the plane of the bar 23 and engages and locks same. It will be understood, that said bolt 1 and attached elements are positioned between the bar 23 and the door 21.

In case an attempt is made to use an oxyacetylene torch or other heating means to 125 burn through a vulnerable part of the door such as that in juxtaposition to the combination lock locking-bar between the lock and the bar 23, the intense heat will melt the fusible part 29 releasing the wire 28 so 130

that the spring 11 may react to lock said auxiliary device, the hook 17 pulling out simultaneously.

It is to be understood that various modifications may be made in my device without departing from the principle of the invention, and that the same may be applied for locking purposes to any structure where its use is admissible.

10 It should be noted that when the cross-bar 7 is released from tension and moves back over the enlargement 3, one or more of the rings 4 is uncovered and dropped down to an eccentric position relative to the bolt 1, and in this position prevents forcing back of the cross-bar. This locking action will occur if the cross-bar moves only enough to uncover a single ring 4.

After this device has been locked as a result of some interference as hereinbefore mentioned, it can be released by an operative who is familiar with the location of the different structures thereof, by drilling a hole through the door at either end of the bolt 25 to permit of insertion of a small tool which can be used to push around either lock-nut 2 or 5 to remove it.

Having described my invention, what I claim as new and desire to secure by Letters Patent, is:

1. The combination with a door having a fixed orificed marginal rib, a shifting-bar movable to and from said rib, a locking-bolt carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to seat it slidably upon the enlargement of said bolt, one or more rings having the same exterior diameter as said enlargement and a larger interior diameter than said bolt mounted loosely on the bolt between said enlargement and said nut, an orificed cross-bar 35 slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been 40 moved to be mounted upon said rings, thence crossing the said lock contactingly and having its other end secured to the door near the lock, another wire releasably linked to said releasable engaging-means, carried thence 45 across a vulnerable part of the door between said lock and said shifting-bar, having its other end secured to the door, and including a part of low melting point overlying said vulnerable part of the door, both said wires 50 being composed of sections, and turnbuckles adjustably uniting the sections.

2. The combination with a door having a fixed orificed marginal rib, a shifting-bar movable to and from said rib, a locking-bolt 55 carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to 60 seat it slidably upon the enlargement of said bolt, one or more rings having the same exterior diameter as said enlargement and a larger interior diameter than said bolt mounted loosely on the bolt between said enlargement and said nut, an orificed cross-bar 65 slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been 70 moved to be mounted upon said rings, thence crossing the said lock contactingly and having its other end secured to the door near the lock, another wire releasably linked to said releasable engaging-means, carried thence 75 across a vulnerable part of the door between said lock and said shifting-bar, having its other end secured to the door, and including a part of low melting point overlying said vulnerable part of the door. 80

3. The combination with a door having a fixed orificed marginal rib, a shifting-bar movable to and from said rib, a locking-bolt 85 carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to 90 seat it slidably upon the enlargement of said bolt, one or more rings having the same exterior diameter as said enlargement and a larger interior diameter than said bolt mounted loosely on the bolt between said enlargement and said nut, an orificed cross-bar 95 slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been 100 moved to be mounted upon said rings, thence crossing the said lock contactingly and having its other end secured to the door near the lock, another wire releasably linked to said releasable engaging-means, carried thence 105 across a vulnerable part of the door between said lock and said shifting-bar, having its other end secured to the door, and including a part of low melting point overlying said vulnerable part of the door, both said wires 110 being composed of sections, and turnbuckles adjustably uniting the sections.

4. The combination with a door having a fixed orificed marginal rib, a shifting-bar movable to and from said rib, a locking-bolt 115 carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to 120 seat it slidably upon the enlargement of said bolt, one or more rings having the same exterior diameter as said enlargement and a larger interior diameter than said bolt mounted loosely on the bolt between said enlargement and said nut, an orificed cross-bar 125 slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been 130 moved to be mounted upon said rings, thence crossing the said lock contactingly and having its other end secured to the door near the lock, another wire releasably linked to said releasable engaging-means, carried thence across a vulnerable part of the door between said lock and said shifting-bar, having its other end secured to the door, and including a part of low melting point overlying said vulnerable part of the door.

enlargement and said nut, an orificed cross-bar slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been moved to be mounted on said rings, thence crossing the said lock contactingly and having its other end secured to the door near the lock, another wire releasably linked to said releasable engaging-means, carried thence across a vulnerable part of the door between said lock and said shifting-bar, having its other end secured to the door near the lock, another wire releasably linked to said releasable engaging-means, carried thence across a vulnerable part of the door between said lock and said shifting-bar, having its other end secured to the door, and including a part of low melting point overlying said vulnerable part of the door.

4. The combination with a door having a fixed orificed marginal rib, a shifting-bar movable to and from said rib, a locking-bolt carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to seat it slidably upon the enlargement of said bolt, rods having frangible connections to opposite ends of said cross-bar and extending slidably through orifices in said fixed rib, each rod having a vertical orifice near its outer end formed with a diminished lower part providing a shoulder and a headed pin of less length than the diameter of the rod seated slidably in said orifice to have its head rest on said shoulder and its lower end depend below the rod when that end of the rod is projected free of and beyond said rib, one or more rings having the same exterior diameter as said enlargement and a larger interior diameter than said bolt mounted loosely on the bolt between said enlargement and said nut, an orificed cross-bar slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been moved to be mounted upon said rings, thence crossing the said lock contactingly and having its other end secured to the door near the lock, and another wire releasably linked to said releasable engaging-means, carried thence across a vulnerable part of the door between said lock and said shifting-bar, having its other end secured to the door, and including a part of low melting point overlying said vulnerable part of the door.

vulnerable part of the door between said lock and said shifting-bar, having its other end secured to the door, and including a part of low melting point overlying said vulnerable part of the door.

5. The combination with a door having a fixed orificed marginal rib, a shifting-bar movable to and from said rib, a locking-bolt carried by said bar, and a lock adapted to releasably secure said bar and bolt in certain positions, of auxiliary locking-means, comprising a headless-bolt threaded at both ends with one end secured in a threaded orifice in said rib, a nut mounted on the inner end of the bolt, said bolt having a cylindrical enlargement spaced from the inner end of the bolt, a cross-bar positioned partially in the plane of said shifting-bar and orificed to seat it slidably upon the enlargement of said bolt, rods having frangible connections to opposite ends of said cross-bar and extending slidably through orifices in said fixed rib, each rod having a vertical orifice near its outer end formed with a diminished lower part providing a shoulder and a headed pin seated slidably in said orifice to have its head rest on said shoulder and its lower end depend below the rod when that end of the rod is projected free of and beyond said rib, one or more rings having the same exterior diameter as said enlargement and a larger interior diameter than said bolt mounted loosely on the bolt between said enlargement and said nut, an orificed cross-bar slidably seated on said bolt and rigidly bracketed on the first-mentioned cross-bar, a coiled spring mounted on said bolt and engaged between said enlargement of the bolt and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been moved to be mounted upon said rings, thence crossing the said lock contactingly and having its other end secured to the door near the lock, and another wire releasably linked to said releasable engaging-means, carried thence across a vulnerable part of the door between said lock and said shifting-bar, having its other end secured to the door, and including a part of low melting point overlying said vulnerable part of the door.

6. The combination with a door having a fixed orificed marginal rib, a shifting-bar movable to and from said rib, a locking-bolt carried by said bar, and a lock adapted to releasably secure said bar and bolt in certain positions, of auxiliary locking-means, comprising a headless-bolt threaded at both ends with one end secured in a threaded orifice in said rib, a nut mounted on the inner

end of the bolt, said bolt having a cylindrical enlargement spaced from the inner end of the bolt, a cross-bar positioned partially in the plane of said shifting-bar and 5 orificed to seat it slidably upon the enlargement of said bolt, rods having frangible connections to opposite ends of said cross-bar and extending slidably through orifices in said fixed rib, each rod having a vertical orifice near its outer end formed with a diminished lower part providing a shoulder and a headed pin of less length than the diameter of the rod seated slidably in said orifice to have its head rest on said shoulder 10 and its lower end depend below the rod when that end of the rod is projected free of and beyond said rib, one or more rings having the same exterior diameter as said enlargement and a larger interior diameter than said 15 bolt mounted loosely on the bolt between said enlargement and said nut, an orificed cross-bar slidably seated on said bolt and rigidly bracketed on the first-mentioned cross-bar, a coiled spring mounted on said bolt and engaged 20 between said enlargement of the bolt 25 and the second-mentioned cross-bar, an adjusting-nut on said bolt engaging the opposite face of the second-mentioned cross-bar, releasable engaging-means on the first-mentioned cross-bar, a wire having one end connected to said releasable engaging-means when the first-mentioned cross-bar has been moved to be mounted upon said rings, thence crossing the said lock contactingly and having its other end secured to the door near the 30 lock, and another wire releasably linked to said releasable engaging-means, carried thence across a vulnerable part of the door between said lock and said shifting-bar, having its other end secured to the door, including a part of low melting point overlying said vulnerable part of the door, both said wires being composed of sections, turnbuckles adjustably uniting the sections, and pulleys mounted upon said door engaging 35 said wires to keep them respectively positioned in certain directions under tension.

Signed at Waterloo, Iowa, this 24th day of Dec., 1921.

CHARLES W. BABCOCK.
